UNITED STATES PATENT OFFICE

142,740

DESIGN FOR WELTING

William E. Phinney, Milton, N. H.

Application July 9, 1945, Serial No. 120,584

Term of patent 14 years

(Cl. D7—6)

To all whom it may concern:

Be it known that I, William E. Phinney, a citizen of the United States, residing at Milton, in the county of Strafford and State of New Hampshire, have invented a new, original, and ornamental Design for Welting, of which the following is a specification, reference being had to the accompanying drawing, forming a part thereof, in which:

Fig. 1 is a view in perspective of a piece of welting showing my new design, and

Fig. 2 is a view of the same in cross section on a greatly enlarged scale.

I claim:

The ornamental design for welting, substantially as shown.

WILLIAM E. PHINNEY.
